UNITED STATES PATENT OFFICE

LEANDRO E. MELÉNDEZ, OF NEW YORK, N. Y.

MAGAZINE PENCIL

Application filed November 1, 1929. Serial No. 404,130.

This invention is directed to an improvement in magazine pencils wherein a lead, stored within a magazine in the end of the pencil, may be selected, withdrawn from the magazine, and delivered into writing position without separation of the pencil parts.

The primary object of the present invention is the provision of a magazine pencil wherein a plurality of magazines are arranged, each adapted to contain leads for use with the pencil, with the leads of one magazine differing in color from the leads of the other magazines, together with means which, through proper manipulation and without separation of the pencil parts, may be operated to select a lead from any desired magazine and introduce it into writing position in the pencil for use.

A further object of the invention is the provision of means by which a lead, in writing position in the pencil, may be readily and conveniently returned to its magazine and another lead selected and introduced into writing position in the pencil without separation of pencil parts.

In general structure, the improved magazine pencil includes a barrel formed at one end with means whereby the lead may be gripped and held in writing relation to the barrel, the barrel above the gripping elements being formed with a central channel in alignment with the gripping elements and with an annular series of independent channels, each adapted to contain a lead with the respective leads preferably of different colors.

Mounted for rotation with respect to the barrel and held against other than rotative movement is a selector containing a receiving channel which is at all times aligned with the central channel in the barrel. The selector is also formed with a radially extending recess communicating with the central channel and adapted under proper rotative movement of the selector to register with any of the annular lead carrying channels in the barrel.

When desiring to introduce a lead into writing position in the pencil, the selector is rotated to align the radial recess therein

with the lead receiving channel containing the selected lead, the pencil is inverted and the lead in the selected lead receiving channel will slide down into the radial recess in the selector and when the pencil is returned to a horizontal position, such lead will find its way into the central channel of the selector in line with the main channel in the barrel. The pencil is then held in an upright position permitting the selected lead to move through and into the gripping elements in the barrel where it may be held by the tightening of such elements for writing purposes.

By a mere obvious reverse of this operation, the selected lead may be returned to its proper lead receiving channel and any other lead in the pencil selected and positioned for subsequent use.

The pencil structure involves indicating means by which the particular lead to be selected may be readily determined, both in manipulating the pencil to use such selected lead and in returning said selected lead to its respective channel for storage after use.

The invention is illustrated in the accompanying drawings, in which:

Figure 1 is a longitudinal section of the improved pencil, showing the same in preferred form.

Figure 2 is a broken plan, partly in section, illustrating particularly the lead pocket indicators and the relation of the selector with the lead pocket.

Figure 3 is a broken perspective of one end of the barrel, showing the lead indicators.

Figure 4 is a section on line 4-4 of Figure 1.

Figure 5 is a broken perspective view of the selector.

Figure 6 is a section on line 6-6 of Figure 5.

Figure 7 is a view in elevation, partly in section, of a modified form of selector.

The improved magazine pencil includes a barrel 1 of hollow construction, closed at the lower end by a plug 2, axially of which is formed a channel 3 of a size to permit free passage of the selected leads therethrough. Beyond the barrel the plug 2 is formed with

more or less resilient gripping fingers 4 of approximately semicircular form in cross section to permit the passage of the lead between them.

5 A clamping element 5 is arranged for threaded connection with the plug 2 and of tapered form beyond the plug, the free end of the clamping element encircling the gripping fingers and formed in one position of the clamping element to clamp the gripping fingers into the lead to hold it for writing purposes, and in the other position of such clamping element to relieve the pressure on the gripping fingers and free the lead for independent movement. This manner of holding the lead in or releasing it from writing position is quite conventional and while the described means is preferred, it is to be understood that any desired means for clamping and releasing the lead may be used, as the present invention is not particularly concerned with this detail.

Within the barrel 1 and extending from the upper surface of the plug 2 toward but materially short of the upper end of the barrel is a lead carrier 6. This carrier, which may be in the form of a cylindrical plug frictionally held within the barrel, is formed with a central channel 7, hereinafter termed the main channel, and which when the carrier is in position, is in direct alignment with the central channel 3 of the plug 2.

Surrounding the main channel of the carrier is a series of lead channels, hereinafter termed lead pockets and indicated at 8. These lead pockets may, if desired, be formed by longitudinally recessing the outer surface of the carrier as the outer wall of each pocket thus formed will be provided by the barrel 1. Of course, the lead pockets may be formed by appropriately boring the carrier, the sole requirement in this particular being that the lead pockets be arranged in a row concentric with and spaced from the main channel 7 of the carrier.

The upper end of the barrel beyond the lead carrier is exteriorly formed to indicate the character of lead in each lead pocket of the carrier. If, as contemplated, these respective leads are to be distinguished by color, then the exterior of the surface of the pencil in the part referred to will have a series of longitudinally arranged spaced areas, each in the longitudinal plane of a particular pocket and each colored to indicate the color of the lead occupying that pocket. These color indicators may, of course, be of any distinguishing characteristic and are indicated at 9.

Fitting over the area of the barrel on which the respective lead indicators 9 are placed is a ferrule 10, in the form of an elongated sleeve which is so connected to the barrel as to permit free rotation of the ferrule without permitting relative longitudinal movement. The ferrule is formed with an

opening 11 through which the respective lead indications 9 are visible as the ferrule is rotated, thus permitting the user to arrange the ferrule in a particular relation to a selected color or other lead indicator, for a purpose which will later appear.

Secured within the ferrule 10 is what may be termed a lead selector 12. This selector may be in the form of a cylindrical block having a diameter slightly less than that of the interior diameter of the barrel and a length permitting the free end of the selector to terminate immediately adjacent the upper end of the lead carrier when the parts are in assembled relation. Thus, the selector is of such length as to fill the barrel beyond the lead carrier, the selector of course extending beyond the barrel and being connected to the ferrule so that, on rotation of the ferrule, the selector will be correspondingly moved.

The selector is formed with a central bore 13 which, when the parts are assembled, is in direct alignment with the main channel 7 of the lead carrier and the central channel 3 of the plug 2. The bore 13 is closed by the ferrule or at the ferrule end of the selector and open at the end of the selector, next the lead carrier. The selector is also formed with a radially arranged opening 14 in the form of a longitudinally extending slot which at its inner end communicates with the bore 13 and preferably opens at its outer end through the outer surface of the selector.

It is, of course, to be understood that, aside from the bore 13 and slot 14, the end of the selector next the lead carrier is solid and forms an abutment to prevent endwise movement of the leads in the pockets when the pencil is inverted unless the slot is aligned with the particular pocket. It is of course understood that the lead pockets and channel in the lead carrier and the bore and slot in the selector are of such diameter relative to that of the leads employed as to permit rather free movement of the leads while of course preventing any appreciable inclined or tilted position of the leads.

Assuming it is desired to use a red lead in the pencil, the ferrule is turned until the red lead indicator 9 is displayed through the opening 11 in the ferrule. In this position of the parts, the slot 14 of the selector is in line with the pocket 8 containing the red lead. The pencil is then inverted and the red lead from the pocket 8 moves longitudinally from said pocket and into the slot 14 in the selector. The pencil is then returned to a substantially horizontal position and the red lead moves from the slot 14 into the bore 13 of the selector.

The pencil is then turned into a vertical or normal writing position and the red lead in the bore 13 of the selector moves through the main channel 7 of the lead carrier through the central channel 3 of the plug 2 and be-

tween the gripping fingers 4. The clamping element 5 is then tightened upon the fingers and the lead clamped and the pencil is ready for use in the usual way.

5 In returning the lead to the pocket, either for the purpose of selecting another colored lead or of housing the particular lead, the clamping element 5 is loosened and the pencil inverted. The lead moves from between the 10 gripping fingers 4 longitudinally between the channels 3 and 7 and into the bore 13 of the selector. The selector is then turned to align the bore 13 with the pocket 8 in which the lead is to be replaced. The pencil is arranged 15 in a horizontal position with the slot 14 downwardly, the red lead passes from the bore 13 of the selector into the slot 14 and as this slot 14 has been aligned with the pocket 8 into which the lead is to be replaced, a simple 20 movement of the pencil into a normal or substantially writing position causes the lead to move from the slot 14 into its particular pocket.

The selector may then be operated to select 25 and position for writing any other lead or the ferrule may be turned so that the opening 11 does not show any lead indicating mark 9. In this position, the slot 14 will be out of alignment with any one lead pocket and the 30 leads of all the pockets will be prevented from endwise movement, no matter what the position of the pencil may be.

The end of the ferrule may be provided 35 with an eraser 15 and the pencil may be further provided with the usual retaining clip 16 and where a clip is used, it is preferred that the clip be formed with an opening 17 to register with the opening 11 in the ferrule, so that the lead indicating marks 9 will be visible 40 through the clip.

While the pencil is primarily designed as a magazine pencil for containing leads of different colors, it will be appreciated that it 45 will be equally serviceable for different leads of the same color but of different degrees of hardness or even of leads which are identical in color and hardness, for with leads of the same color but of different degrees of hardness, the selection permitted will enable the user to select the desired lead, while with 50 leads of similar color and similar hardness, the pencil permits a convenient and simple renewal of a lead from time to time as may be required.

55 Of course, it is understood that the pencil may be made of different materials and exteriorly ornamented to any desired degree and in any particulars, thereby providing a magazine pencil which, when once charged, 60 will permit the user to select the desired lead and readily and conveniently place the same in position for writing without the necessity of separating any parts of the pencil or directly handling the lead.

65 The above description is illustrative of the

novel features of the improved magazine pencil and for commercial reasons it is preferred to indicate certain details which simplify the construction and insure a more perfect operation for the feeding of the lead. For example, as shown in the preferred form, the channel 7 in the lead carrier, the channel 3 in the plug 2 and the gripping fingers 4 may be constructed of a single tube-like element fitted tightly in the longitudinal axial opening in the lead carrier 6, so that beyond the selector there is a single unbroken tube through which the lead may pass freely without possibility of obstruction.

In the modified form, this lead tube, here indicated at 18, may be carried directly by the selector, here indicated at 19, but which is constructed identically with the selector previously described. This tube 18 is a continuation of the bore 13 of the selector and of course passes loosely through the axial opening of the lead carrier, through the plug and is terminally formed with the gripping fingers 4.

Furthermore, in the mounting of the selector within the ferrule, said selector may be formed at the end remote from the lead carrier with a pocket to receive the eraser and with an exterior fixed band 20 on which the ferrule proper is threaded, thus uniting the ferrule and selector for simultaneous rotative movement while permitting the selector to fit within the barrel and the ferrule to pass over the barrel, as indicated in Figure 1.

If desired, the barrel and ferrule may be formed with conventional cooperating projections and indentations or grooves and projections, as indicated generally at 21, whereby the ferrule and thereby the selector may be accurately centered in any adjustment relative to the lead pocket and held against casual relative movement during the use of the pencil.

It is to be noted that the selector 12 is in the form of a hollow cylinder which is closed at the end next the lead carrier but open at the opposite end. The interior of the cylinder is fully unobstructed except for the wall defining the central bore 13 and slot 14. This provides a very considerable area within the selector freely accessible from the upper end of the pencil, which area is designed to serve as a storage space for auxiliary leads for the convenient recharging of the lead pockets of the carrier when necessary. The open end of the storage compartment of the selector is designed to be closed by the eraser, as clearly shown in Figures 1 and 5, so that by simply removing the eraser, the auxiliary leads in the storage chamber may be removed for recharging of the lead pockets of the carrier.

What is claimed to be new is:

1. A magazine pencil including a barrel terminating in a writing point, a lead carrier fixed within the barrel immediately above

the writing point and formed to provide a central channel in line with the writing point and a series of concentric channels for the reception of different leads, and means operative beyond the carrier with respect to the writing point to be positioned to receive a lead from a particular lead channel and transfer such lead to the central channel through longitudinal tilting of the pencil.

10 2. A magazine pencil including a barrel, a fixed lead carrier in the barrel, said carrier having a central channel in line with the writing point, a series of concentric lead-receiving channels, and a member arranged above the carrier formed with lead-receiving means to register with the central channel and with one of the lead channels in any position of the member, whereby lead may be transferred from a selected lead channel to the central 20 channel merely through a longitudinal tilting of the pencil.

25 3. A magazine pencil including a barrel, a lead carrier therein formed with a central channel communicating with the writing point of the barrel and a series of concentric lead-receiving channels, and a member mounted for rotation in the barrel above the lead carrier and formed with a longitudinally ranging slot having a radial length to include the central channel and any selected lead channel, whereby on inversion of the pencil a lead from a selected lead channel may be transferred to the member and positioned in line with the central channel by mere longitudinal tilting of the pencil.

40 4. A magazine pencil including a barrel, a lead carrier therein formed with a central channel communicating with the writing point of the barrel and a series of concentric lead-receiving channels, and a member mounted for rotation in the barrel above the lead carrier and formed with a longitudinally ranging slot having a radial length to include the central channel and any selected lead channel, the member blocking all lead channels other than the selected channel.

45 5. A magazine pencil including a barrel, a lead carrier therein formed with a central channel communicating with the writing point of the barrel and a series of concentric lead-receiving channels, and a member mounted for rotation in the barrel above the lead carrier and formed with a longitudinally ranging slot having a radial length to include the central channel and any selected lead channel, and means operative from the exterior of the pencil for actuating the member.

60 6. A magazine pencil including a barrel, a lead carrier therein formed with a central channel communicating with the writing point of the barrel and a series of concentric lead-receiving channels, a member mounted for rotation in the barrel above the lead carrier and formed with a longitudinally rang-

ing slot having a radial length to include the central channel and any selected lead channel, means operative from the exterior of the pencil for actuating the member, and means for indicating the position of the slot in the member.

In testimony whereof I affix my signature.
LEANDRO E. MELENDEZ.
